DESIGN FOR A MOTION PICTURE PROJECTOR

Thomas J. Morgan, Chicago, Ill., assignor to
Universal Stamping & Mfg. Co., Chicago, Ill.,
a corporation of Illinois

Application March 20, 1940, Serial No. 91,095

Term of patent 14 years

To all whom it may concern:

Be it known that I, Thomas J. Morgan, a citizen of the United States, residing at Chicago, in the county of Cook and State of Illinois, have invented a new, original, and ornamental Design for a Motion Picture Projector, of which the following is a specification, reference being had to the accompanying drawings, forming part thereof.

Figure 1 is a front perspective view taken from one side of the projector.

Figure 2 is a front perspective view taken from the opposite side of the projector.

Figure 3 is a rear perspective view of the projector.

Figure 4 is a front elevational view of the projector.

I claim:

The ornamental design for a motion picture projector, substantially as shown.

THOMAS J. MORGAN.
